ABSTRACT OF THE DISCLOSURE

A machine for mounting a label on a web with the web overlying and protecting a face of the label. A swinging framework is pivotally mounted in the machine and carries a first roll and a second roll interconnected for turning in unison and in opposite directions. The web is guided crosswise of and in engagement with the first roll. A back-up roll is rotatably mounted opposite the second roll. The label is guided between the second roll and the back-up roll. Initial outward movement of the web causes the framework to swing to bring the second roll into position to grip the label against the back-up roll. Further outward movement of the web causes the first roll to turn and drive the second roll. The second roll advances the label into face-to-face engagement with the web.

This invention relates to a machine for mounting a label on a web of transparent pressure sensitive tape.

It is often desirable to cover a label, such as an address label, with a layer of transparent pressure sensitive tape to protect information on the label and to ensure firm attachment of the label to a package. However, manipulation of a web of pressure sensitive tape can be inconvenient and ensuring a smooth wrinkle free attachment of label to tape can often be difficult. An object of this invention is to provide a machine which mounts a label on a web of pressure sensitive tape.

A further object of this invention is to provide a machine from which a web of pressure sensitive tape can be withdrawn and in which a label is advanced into face-to-face engagement with the web as the web is withdrawn.

A further object of this invention is to provide a machine of this type in which advance of the web drives mechanism which advances the label at the same speed at the tape is advanced, so that the web and label advance into wrinkle-free engagement.

A further object of this invention is to provide a machine of this type in which, as the web is initially advanced, a label gripping roll is advanced into engagement with the label and in which further advance of the web drives the label gripping roll to advance the label into engagement with the web.

A further object of this invention is to provide a power drive for such a machine which withdraws the tape and advances the label and tape into engagement.

A further object of this invention is to provide such a machine which protects the tape against dust and the like before the tape is dispensed.

The above and other objects and features of the invention will be apparent to those skilled in the art to which this invention pertains from the following detailed description, and the drawings, in which:

FIG. 1 is a view in side elevation of a label mounting machine constructed in accordance with an embodiment of this invention;

FIG. 2 is a plan view of the machine illustrated in FIG. 1;

FIG. 3 is a view in end elevation of the machine shown in FIGS. 1 and 2, parts thereof being broken away and in section to reveal interior construction;

2

FIG. 4 is a view in vertical section of the machine illustrated in FIGS. 1 to 3, inclusive, a web of tape and a roll thereof being shown in dot-dash lines;

FIG. 5 is a view in section taken on the line 5—5 in FIG. 4;

FIG. 6 is a view in section taken on the line 6—6 in FIG. 1, a label being shown in dot-dash lines and a web of tape being shown in full lines;

FIG. 7 is an enlarged view in section taken on the line 7—7 in FIG. 6;

FIG. 8 is an enlarged view in section taken on the line 8—8 in FIG. 6;

FIG. 9 is an enlarged view in section taken on the line 9—9 in FIG. 4;

FIG. 10 is a view in section taken on the line 10—10 in FIG. 9;

FIG. 11 is a fragmentary view in side elevation of a swinging assembly forming a portion of the machine;

FIG. 12 is a fragmentary view in end elevation on an enlarged scale of a drive roll forming a part of the machine, a fragmentary portion of the web of pressure sensitive tape being shown in association therewith, the other portions of the machine being omitted for clarity;

FIG. 13 is a view in section taken generally on the line 13—13 in FIG. 4, parts being broken away in order to reveal internal construction;

FIG. 14 is a fragmentary view in side elevation of a machine constructed in accordance with another embodiment of this invention;

FIG. 15 is a view in section taken on the line 15—15 in FIG. 14, and

FIG. 16 is a plan view of a package with a label and tape attached thereto.

In the following detailed description, and the drawings, like reference characters indicate like parts.

In FIGS. 1 to 4, inclusive, is shown a label mounting machine 15 constructed in accordance with an embodiment of this invention. The machine includes a base plate 16 to which a housing 17 is pivotally mounted on pivot pins 18 (FIGS. 1 and 2) which are mounted in sockets 19 (FIG. 4) in the base 16. The housing 17 includes side wall panels 21 and 22 (FIG. 1), a generally angle shaped upper frame panel 23, a generally angle shaped nose panel 24, and a guide plate 26, all of which can be rigidly connected together as by welding or the like. On the side wall panels 21 and 22 are mounted shaft supports 27 (FIG. 4) and 28 (FIG. 3) which can carry a cross rod 29 on which a roll of transparent pressure sensitive tape 31 can be mounted. As shown in FIG. 4, each of the shaft supports is provided with a slot 32 in which an end portion of the rod 29 is received.

A web of tape 33 can be withdrawn from the roll 31 and passes therefrom under a roller 34, which is rotatably mounted on a swinging framework 35. The web is withdrawn from the roll 31 with the adhesive coated side up, and the adhesive coating adheres to the roller 34. As shown in FIG. 12, the face of the roller 34 is provided with a plurality of spaced narrow lengthwise ribs 34a so that the tape adheres only to outer edges of the ribs. The roller 34 can be made of a smooth surfaced plastic material such as that commonly known as "Delrin" so that, although the web adheres thereto, the web is readily releasable therefrom. As the web is drawn outwardly, the web drives and turns the roller 34. A pinion gear 36 is mounted on and attached to the roller 34 by screw fasteners 37 (FIG. 11). The pinion gear 36 meshes with and drives a pinion gear 38 mounted on a roller 39 which is also rotatably mounted on the swinging framework 35.

The swinging framework 35 includes side plates 41 and 42 (FIG. 13), which are pivotally mounted on a cross-rod 43. The crossrod 43, in turn, spans the side

wall panels 21 and 22 with end portions thereof being received and supported at openings 44 and 46 in the side wall panels as shown in FIG. 13. The side plates 41 and 42 are linked by a frame plate 47 to which the side plates are attached. Swinging of the swinging framework 35 in a counter-clockwise direction is limited by a cross-rod 48, which spans the side wall panels 21 and 22. Tension springs 49 and 51 are attached to the crossrod 48 and to studs 52 and 53 mounted on the side plates 41 and 42, respectively, to urge the swinging frame 35 counter-clockwise as indicated in FIG. 4.

The roller 39, as shown in FIG. 13, includes sections 54 which are of large diameter and other sections 56 of small diameter. As shown in FIG. 6, the lower portion of the guide plate 26 terminates in teeth 57 which are separated by slots 58. The sections 54 of large diameter are aligned with the slots 58. As shown in FIGS. 7 and 8, as the web 33 is drawn outwardly, the swinging frame 35 swings from the FIG. 7 position to the FIG. 8 position in which the sections 54 of large diameter extend through the slots 58. In this position, the sections 54 can cooperate with an idle back-up roll 61 to engage a label 62 therebetween. Then, as the web is drawn further outwardly, the label is fed downwardly along the teeth 57 and into face-to-face engagement with the web 33. The roller 39 can be formed of rubber or rubber-like material so that the label is firmly gripped thereby. An idle pressing roll 63 is disposed adjacent lower edges of the teeth 57, and the label and the tape pass around the idle roll 63 to press the label into firm engagement with the tape. The idle roll 63 is provided with a facing sleeve 64 of smooth plastic material such as that known as "Teflon" so that the web of tape is readily releasable therefrom. The rolls 61 and 63 are rotatably mounted in bearings mounted in the side wall panels 21 and 22, as shown in FIG. 5. From the idle roll 63, the web of tape with the label attached thereto passes over an idle roll 66 which is mounted in bearings 67 attached to the base 16. The idle roll 66 is arranged to guide the tape into engagement with the idle roll 63. Outboard of the roll 66, a tape cut-off knife 68 is mounted on the nose panel 24.

When a label 62 is to be mounted on the web 33, the label is positioned on the guide plate 26, as shown in FIGS. 6 and 7. Side guides 71 are mounted on guide plate 26 for positioning the label. Each of the side guides 71 is mounted on a guide block 72 (FIGS. 9 and 10). Each guide block extends through a slot 73 in the guide plate 26. Each guide block is provided with a transverse bore 74 through which the cross rod 43 extends. A thumb screw 76 mounted in each guide block is engageable with the crossrod 43 as shown in FIGS. 9 and 10 to lock the guide blocks and the side guides in position. As shown in FIG. 9, each side guide 71 is of angle shape, and the side guides 71 direct the label 62 (FIG. 6) downwardly and across the guide plate 26.

When the label mounting machine is to be used, a label 62 is placed on the guide plate 26 in the position shown in FIG. 6 between the side guides 71 and with the face thereof which carries indicia down. The label can slide downwardly into engagement with the web 33 in the position shown in FIG. 7. Then, as the web is drawn outwardly, the swinging framework 35 moves from the FIG. 7 position to the FIG. 8 position, where the large diameter sections 54 of the roller 39 grip the label against the idle roller 61. Then, as the web is withdrawn further, the label 62 is fed downwardly and the web and label pass under the idle roll 63 which serves as a pressing roll and presses the label and web into firm face-to-face engagement. The diameter of the roller 34 and the diameter of the large sections 54 of the roller 39 are approximately equal and the gears 36 and 38 are arranged to turn the rollers 34 and 39 at equal speeds but in opposite directions so that the web and the label advance at approximately equal speeds. However, the effective diameter of the roller 34 can be

slightly less than that of the large sections 54 of the roller 39 so that the web is drawn tight as it comes into engagement with the label 62.

When the label has been pressed into face-to-face engagement, a further portion of the web is drawn outwardly until there is a border of the tape of the web surrounding the label. Then the label and tape surrounding it are cut off from the remainder of the web and are mounted on a package 81 as shown in FIG. 16, and the tape covers and protects the label and indicia written thereon, but the indicia can be read through the transparent tape.

In FIGS. 14 and 15 is shown a machine 115 which is generally similar to the machine already described but includes a power drive mounted on a side wall panel 122 thereof. Mechanism inside a housing 117 thereof can be substantially identical with the mechanism already described and includes an idle back-up roll 161 (FIG. 15) and a driven pressing roll 163. Portions of the rolls 161 and 163 inside the housing are similar in construction to corresponding portions of the rolls 61 and 63, respectively, of the machine shown in FIGS. 1-13 inclusive. The roll 163 is provided with a shaft extension 201 (FIG. 15) on which a worm wheel 202 is mounted. The worm wheel 202 meshes with a worm gear 203 (FIG. 14) rotatably mounted in bearings 204 and 206, which are attached to the side wall panel 122. A pinion 207 mounted on a worm shaft 208 meshes with a pinion 209 mounted on a motor shaft 210. The motor shaft 210 is driven by a motor 211 mounted on the side wall panel 122. Power from the motor drives the roll 163 to draw an adhesive-coated web 133 outwardly and into engagement with a label 162. As shown in FIG. 15, an edge section of the web 133 engages a facing sleeve 164 of the roll while the label 162 overlies the major portion of the web 133, the web engaging the facing sleeve outboard of the label.

Having described my invention, what I claim as new and desire to secure by letters patent is:

1. A machine for mounting a label on a web which comprises a housing, a swinging framework pivotally mounted in said housing, a first roll means and a second roll means rotatably mounted on said swinging framework in parallelism, means interconnecting said first and second roll means for turning in unison and in opposite directions, means for guiding the web crosswise of and in engagement with the first roll means, a back-up roll rotatably mounted in said housing opposite the second roll means, means for guiding the label between the second roll means and the back-up roll, initial outward movement of the web causing the framework to swing to bring the second roll means into position to grip the label against the back-up roll, further outward movement of the web causing the first roll means to turn and drive the second roll means, the second roll means advancing the label into face-to-face engagement with the web, the swinging framework swinging away from the back-up roll when tension on the web is relaxed, whereby a label-receiving gap is formed between the back-up roll and the second roll means.

2. A machine as in claim 1 wherein the web is transparent and adhesive-coated on one face, and means is provided for advancing the label into face-to-face engagement with the adhesive-coated face.

3. A machine as in claim 2 wherein the adhesive coated face of the web engages the first roll means at a portion of the periphery thereof.

4. A machine as in claim 3 wherein the first roll means is provided with a plurality of spaced lengthwise ribs and the adhesive-coated face engages only ridges of the ribs.

5. A machine as in claim 1 wherein the web passes over a pressing roll outboard of the swinging framework, whereby the label is pressed against the web by the pressing roll as the web passes around the pressing roll.

6. A machine as in claim 5 wherein a guide roll is disposed outboard of the pressing roll and guides the web so that, as the web is pulled outwardly, the web and label engage a predetermined portion of the periphery of the pressing roll.

7. A machine as in claim 5 wherein the web is adhesive-coated on the face thereof which is opposed to the pressing roll so that a portion of the adhesive-coated face of the web outboard of the label engages the pressing roll.

8. A machine as in claim 5 wherein the web is adhesive-coated on the face thereof which is opposed to the pressing roll so that a portion of the adhesive-coated face outboard of the label engages the pressing roll, and means is provided for driving the pressing roll to draw the web and the label into face-to-face engagement.

9. A machine as in claim 1 wherein the swinging framework is resiliently urged to a position in which the second roll means is spaced from the back-up roll to provide a space therebetween for receiving the label.

10. A machine for mounting a label on a web which comprises a first roll means and a second roll means rotatably mounted in parallelism, means interconnecting said first and second roll means for turning in unison and in opposite directions, means for guiding the web crosswise of and in engagement with the first roll means, a 25 back-up roll rotatably mounted opposite the second roll means, means for directing the label between the second roll means and the back-up roll, outward movement of

the web causing the first roll means to turn and drive the second roll means, the second roll means advancing the label into face-to-face engagement with the web.

11. A machine as in claim 10 wherein the web passes over a pressing roll outboard of the first roll means, whereby the label is pressed against the web by the pressing roll as the web passes around the pressing roll.

12. A machine as in claim 11 wherein the web is adhesively coated on the face thereof which is opposed to the pressing roll so that a portion of the adhesive coated-face outboard of the label engages the pressing roll, and means is provided for driving the pressing roll to draw the web and the label into face-to-face engagement.
